(57) **CLAIM**

The ornamental design for a display device, as shown and described.

DESCRIPTION

FIG. 1 is a perspective view of a first embodiment of a display device;

FIG. 2 is a front view of the first embodiment, with the rear view being a mirror image thereof;

FIG. 3 is a left side view of the first embodiment, with the right side view being a mirror image thereof;

FIG. 4 is a top view of the first embodiment, with the bottom view being a mirror image thereof;

FIG. 5 is a perspective view of the first embodiment of the display device with an image, such as icons, displayed thereon, the image forming no part of the claimed design;

FIG. 6 is a front-top perspective view of a second embodiment of a display device;

FIG. 7 is a front view of the second embodiment;

FIG. 8 is a rear view of the second embodiment;

FIG. 9 is a left side view of the second embodiment, with the right side view being a mirror image thereof;

FIG. 10 is a top view of the second embodiment, with the bottom view being a mirror image thereof;

FIG. 11 is rear-bottom perspective view of the second embodiment; and,

FIG. 12 is a front-top perspective view of the second embodiment of the display device with an image, such as icons, displayed thereon, the image forming no part of the claimed design.

The broken lines shown in the drawings represent environment only and form no part of the claimed design.
